UNITED STATES PATENT OFFICE.

ROBERT C. COLE, OF WEST HARTFORD, CONNECTICUT, ASSIGNOR TO THE JOHNS-PRATT COMPANY, OF HARTFORD, CONNECTICUT, A CORPORATION OF CONNECTICUT.

INSULATING-BUSHING FOR ELECTRICAL SERVICE-BOXES.

No. 918,969.

Specification of Letters Patent.

Patented April 20, 1909.

Application filed December 11, 1908. Serial No. 466,964.

To all whom it may concern:

Be it known that I, ROBERT C. COLE, a citizen of the United States, residing at West Hartford, county of Hartford, State of Connecticut, have invented certain new and useful Improvements in Insulating-Bushings for Electrical Service-Boxes, of which the following is a full, true, and concise specification.

10 The invention is an improvement in the inclosures of electrical apparatus such as are generally known as fuse or service-boxes, and consists of a new means for fastening the insulating bushings within the apertures in 15 the walls of such boxes, the said apertures and bushings being for the accommodation of the electric circuit wires which lead to the apparatus within the box.

The object of the invention is to improve 20 the security with which said bushings are held in place, to render the connection substantially moisture and water proof, and to provide a mode of attachment that will not be liable to deterioration under vibration or 25 other conditions of severe service and also to reduce the cost and facilitate the assemblage of the parts.

The drawings forming a part hereof show, 30 in Figure 1, a perspective view of an ordinary fuse or service box of the kind herein referred to. Fig. 2 is an enlarged longitudinal section of the front wall of said box, showing a bushing also in section, secured therein according to my invention. Fig. 3 35 is a similar view with the several parts separated as before assemblage, the bushing in this figure being shown in elevation.

The box shown in Fig. 1 is provided with the usual hinged cover 1 and locking nut 2, 40 and is intended to contain electrical fuses or other apparatus which for known reasons are required to be safely inclosed. The box and cover are made of metal. The circuit wires lead to the interior apparatus through 45 appropriate apertures formed in the walls 3 thereof, and insulating bushings are desirable for such apertures in order to separate the circuit wires absolutely from the metal of the box. The box illustrated is adapted 50 to accommodate the circuit wires of a three-wire system.

In accordance with my invention, the bushings for the apertures in the box, are formed with a head or flange 4 adapted to 55 rest against the marginal portion of the box

wall, immediately adjacent to the aperture, and with a barrel portion 5 occupying the aperture and protruding more or less beyond it as desired. The exterior formation of the said barrel portion is coöordinated with the formation of the inner wall of the aperture so as to provide opposing abutments respectively thereon and within the annular crevice between the two parts; for example, the barrel portion 5, just behind the head or flange 4, is provided with a groove or recess which forms an abutment ledge, indicated at the point marked 6, and the aperture in the box wall is convergingly tapered toward the head of the flange, so that its most contracted end affords a similar ledge or abutment, indicated at the point marked 7, the two abutments being disposed in opposition to each other so as to withstand thrust in a longitudinal direction or parallel with the axes of the bushing and aperture. Other coöordinated formations may be provided, however, that will produce opposing abutments of similar function, but the form described is of advantage in that it provides a tapered or somewhat funnel-shaped entrance to the interior of the crevice or annular space between the bushing and the wall, this being due to the taper of the aperture. Into this entrance it is intended that a plastic interlocking and sealing member shall be forced for the purpose of filling up the space between the abutments with a more or less rigid pressure-transmitting medium, and thus locking the bushing in place.

The sealing member, as indicated in Fig. 3, consists of a ring 8 of plastic metal such as soft lead or other dense plastic or semi-plastic material capable of accommodating its shape to the shape of the crevice under a suitable pressure. Before insertion, the ring conforms in size and shape to the shape of the crevice and is intended to be pressed or crowded into the latter by means of any suitable pressure instrument, so that it flows inwardly toward the head of the bushing, entirely and compactly filling the space between the two abutments therein, not only locking the bushing in place, as above stated, but forming a hermetic connection between the parts.

I claim the following as my invention:

1. The combination, with the box or inclosure of electric fuses or other electrical apparatus, having an aperture through the wall

2

thereof for the introduction of a circuit-wire, of an insulating bushing for said aperture having its exterior peripheral formation co-ordinated with the formation of the wall of 5 said aperture to provide opposing abutments in the crevice therebetween, said abutments being disposed to withstand thrust parallel with and in the direction to remove said bushing, and a plastic metal 10 locking ring crowded into the space between said crevice abutments and serving as an interlocking thrust-transmitting medium between the same.

2. The combination, with the box or inclosure of electric fuses or other electrical apparatus, having an aperture through the wall thereof for the introduction of a circuit wire, of an insulating bushing for said aperture having a flanged head thrusting against the 15 wall of said inclosure, and behind said head an abutment disposed in opposition to an abutment formed in said aperture, and a plastic metal ring crowded into the space between said abutments to prevent the removal of the bushing.

3. The combination, with the inclosure for electric fuses or other electric apparatus having a flared or tapered aperture through the 20

wall thereof for the introduction of a circuit wire, of an insulating bushing for said aperture having a flange thrusting against the margin of the smaller end of said tapered aperture, and having behind said flange and said smaller end an opposing abutment within the aperture and a plastic ring crowded into the crevice between said abutment and the tapered end of the aperture.

4. The combination, with the inclosure of electric fuses or other apparatus having a flared or tapered aperture through the wall 30 thereof for the introduction of a circuit wire, of an insulating bushing for said aperture having a grooved exterior formation disposed within said aperture and a plastic ring pressed through the larger end of said aperture into interlocking engagement with said grooved formation and said tapered aperture to prevent removal of said bushing.

45 In testimony whereof, I have signed my name to this specification in the presence of 50 two subscribing witnesses.

ROBERT C. COLE.
